UNITED STATES PATENT OFFICE.

PAUL A. RECORDS, OF PERRYTON, TEXAS.

SINGLE-CYLINDER DOUBLE-ACTING PUMP.

1,411,515.

Specification of Letters Patent. Patented Apr. 4, 1922.

Application filed April 18, 1921. Serial No. 462,299.

To all whom it may concern:

Be it known that I, PAUL A. RECORDS, a citizen of the United States, residing at Perryton, in the county of Ochiltree and State of Texas, have invented certain new and useful Improvements in Single-Cylinder Double-Acting Pumps, of which the following is a specification, reference being had to the accompanying drawings.

10 The present invention has for its purpose the provision of a pump of this character involving a single cylinder containing two pistons and valves connected in such wise that when operated, the water or other fluid may be pumped or elevated upon upward and downward strokes of the pump rod.

Another purpose involves the provision of a pair of pistons and valves, one valve carried by each piston, in combination with 20 means operatively gearing the pistons together, so as to operate in unison, whereby one or the other of the pistons will act to impart a lifting movement to the water or other fluid, so that at all times a continuous 25 flow of fluid may be allowed to discharge from the pump.

Still another purpose is the provision of a pump of this character, wherein a single reciprocating pump rod is employed for actuating the pistons, which are so operatively connected, that upon movement of one piston, the other operates toward or from the first piston, thereby creating a continuous lifting of the fluid.

30 A further purpose involves the provision of fluid lifting means of a continuous discharging type particularly suitable for use in connection for well pumping, to insure a continuous flow of water from the well 35 pump.

While the design and construction at present illustrated and set forth is deemed preferable, it is obvious that as a result of a reduction of the invention to a more practical 45 form for commercial purposes, the invention may be susceptible of changes, and the right to these changes is claimed, provided they are comprehended within the scope of what is claimed.

50 The invention comprises further features and combination of parts, as will be herein-after set forth, shown in the drawings and claimed.

In the drawings:

55 Figure 1 is a sectional view through the

improved single cylinder double acting pump constructed in accordance with the invention.

Figure 2 is a vertical sectional view at right angles to that shown in Figure 1 taken 60 on line 2—2 thereof.

Figure 3 is a vertical sectional view through a modified structure of pump, wherein the pistons are operatively geared together by means of a modified structure. 65

Figure 4 is a sectional view of the central portion of the cylinder of the pump shown in Figure 3, at right angles thereof.

Referring to the drawings, 1 designates a cylinder which may be any suitable length 70 or diameter suitable for the purpose, and mounted upon the cylinder and secured thereto in any suitable manner preferably by shrinking or otherwise is a flanged ring 2. This ring 2 is threaded into the upper end 75 of an elongated steel tube or barrel 3, which may be any suitable length, and into the lower end of which the water or other fluid is adapted to enter, to be lifted to the upper end of the cylinder 1. By the provision of 80 the ring 2, the cylinder is connected to the steel tube or barrel rigidly. The cylinder 1 is designed to extend down to the bottom of the tube or barrel, so that the water or other fluid to be lifted may be easily and 85 quickly drawn into the cylinder. The lower end of the cylinder is provided with a plurality of arcuate recesses or openings 4, so that the lower end of the cylinder will be spaced at intervals from the bottom of the 90 tube or barrel, in order to permit the water or other fluid to enter the cylinder.

A top or cover 5 is provided for the cylinder, and the upper circular wall has a packing gland or stuffing boxing 6, through 95 which the pump rod 7 reciprocates. The upper end of the pump rod 7 is threaded as at 8, there being a handle 9 secured thereon by the upper and lower nuts 10, above and below the handle, so as to hold the handle in place.

The flange 11 of the cover or top engages about the upper end of the cylindrical wall of the cylinder 1, and the lower part of this flange at diametrically opposite points has 105 slots 12, and the edges of the slots terminate in ears 13 extending at right angles to the flange, and receive bolts 14, for drawing the flange tight about the cylinder. The top or cover 5 has a discharge spout 15, to 110

which a hose or the like may be coupled, for carrying off the water or other fluid as it is lifted.

Journalized in bearings of the cylinder 1 at diametrically opposite points are upper and lower transverse pins or journals 16 and 17, the ends of which are swaged to provide heads 18, to hold the journals or pins in place. Mounted upon the journals are upper and lower sprocket wheels 19 and 20, there being spacing sleeves 21 mounted upon the journals or pins between the diametrically opposite parts of the wall of the cylinder 1, so as to hold the sprockets centrally located on the journals.

Passing about the sprockets 19 and 20 is a sprocket chain 22, and mounted in the lower part of the cylinder 1 is a piston rod 23. The rod 7 also constitutes a piston rod, therefore the adjacent ends of the rod 7 and the rod 23 are connected to opposite sides of the sprocket chain 22, by means of cotter pins 24. Each cotter pin straddles a link in the chain, or one side of a link, and is passed through an opening in the end of its respective rod. The ends of the cotter pin are clinched or bent laterally, so as to insure a rigid connection between the two rods and the chain. Obviously when the pump rod 7 is moved downwardly, the piston rod 23 will move upwardly, and vice versa.

Reciprocating in the cylinder are upper and lower pistons 25 and 26. The piston 25 has an opening through which the pump rod 7 passes with frictional engagement, there being a dowel pin 27 threaded through the piston and into the rod, so that the piston 25 may move with the rod. The piston 25 has an annular groove, wherein a piston ring 28 is mounted, in order to have a wiping engagement with the inner surface of the cylinder, as the piston reciprocates. The piston 26 is fastened to the lower end of the piston rod 23 by means of the upper and lower nuts 29 and 30, which are threaded upon the rod, to hold the piston rigidly thereon. The rod 23 passes through the piston, in order to carry the nuts 29 and 30 above and below the piston. The piston 26 also has a groove 28^a, to receive a piston ring 28^b, to provide a wiping engagement with the inner surface of the cylinder.

The pistons 25 and 26 are provided with openings 31 and 32, there being flap valves 33 and 34 secured on the upper faces of the pistons by means of rivets 35, whereby the valves may automatically close and open the openings 31 and 32. In fact the flap valves are constructed of any suitable pliable material, such as leather or the like, so that they will easily open on the downward movements of the piston, due to the pressure of water beneath them, and automatically close upon upward strokes of the pistons, due to the pressure of water above. Therefore it is ob-

vious that as the pump rod 7 is reciprocated, power being imparted thereto by any suitable means, preferably in this instance by means of manual power applied to the handle 9 the sprocket chain 22 is operated, which in turn reciprocates the piston rod 23. When the pump 7 moves downwardly, the piston rod 23 moves upwardly, and the water or other fluid which has previously passed through the opening 32 on the downward stroke of the piston 26 will automatically close the flap valve 34. The water or other fluid previously contained below the piston 25 will open the flap valve 33, and locate above the piston. Obviously on the upward stroke of the piston 25, the water thereabove will be elevated, while on the downward stroke of the piston 26, water below the piston 26 will pass through the opening 32, automatically opening the valve 34, and locate in the cylinder 1 above the piston 26. The water then above the piston 26 will be lifted owing to its pressure closing the flap valve 34 on the upward stroke of the piston 26. Continuous reciprocating movements of the pump rod 7 will insure a constant lifting of the water or other fluid, as one or the other of the pistons is at all times imparting a lifting action to the water or other fluid.

In Figures 3 and 4 the structure is slightly modified, and instead of the endless chain 22, the adjacent parts of the rods 7^a and 23^a are provided with rack teeth 36, which mesh with the pinion or gear 37, which is mounted upon a pin or shaft 38. A metallic boxing or coupling 39 connects the adjacent ends of the rods 7^a and 23^a, so as to not only hold the rack teeth in connection with the pinion or gear, but also with the rods, during their reciprocating movements. Obviously upon the downward movement of the rod 7^a movement will be imparted to the gear or pinion, which in turn will impart an upward movement to the rod 23^a. The pin or shaft 38 is mounted in bearings of the boxing or coupling 39, so as to insure holding the parts connected together operatively.

The boxing or coupling 39 is also centrally spaced in the cylinder 1 by means of spacing sleeves 31^a, and the shaft or pin 38 has its ends swaged as at 40, to hold the same in position.

The invention having been set forth, what is claimed as being useful is:

1. In an operating mechanism for an opposing piston pump, a cylinder provided with an inlet at one end and a discharge opening at the other end, opposing pistons in said cylinder and provided with openings and valves for controlling the fluid through said openings, opposing piston rods offset from and operable toward and from each other in directions longitudinally through the cylinder, upper and lower spaced jour-

nals located between the pistons, revolute members rotatably mounted upon said journals, sleeves upon the journals on opposite sides of the revolute members for holding them centrally disposed midway between the opposing parts of the wall of the cylinder, and means operatively connecting said revolute members and in turn connected to the adjacent ends of said rods, whereby upon operating one of said rods, both rods move from and toward each other, thereby correspondingly operating the pistons.

2. In an opposing piston pump, a cylinder having its opposite ends provided with inlet and discharge openings, opposing piston rods operable longitudinally through the cylinder toward and from each other and in

offset planes, opposing pistons movable with said rods and provided with openings and valves controlling the fluid through the openings, upper and lower spaced journals fixed in the opposing parts of the wall of the cylinder, revolute members mounted upon the journals, spacing sleeves carried by the journals on opposite sides of the revolute members, an endless connector engaging said revolute members, and means comprising a cotter pin detachably connecting the endless connector and the adjacent ends of the piston rods, whereby upon moving one rod, movement is imparted to the other.

In testimony whereof I hereunto affix my signature.

PAUL A. RECORDS.
